DESIGN FOR A MAILBOX

Albert V. Ocone, Hamden, Conn., assignor to Dexter Company, Incorporated, New Haven,
Conn., a corporation of Connecticut

Application January 16, 1946, Serial No. 125,615

Term of patent 3½ years

(Cl. D74—9)

To all whom it may concern:

Be it known that I, Albert V. Ocone, a citizen of the United States, residing at Hamden, in the county of New Haven and State of Connecticut, have invented a new, original, and ornamental Design for a Mailbox, of which the following is a specification, reference being had to the accompanying drawing, forming part thereof.

Fig. 1 is a an edge view of a mailbox showing
my new design;

Fig. 2 is a front face view thereof; and

Fig. 3 is a perspective view of the mailbox on a larger scale.

I claim:

The ornamental design for a mailbox, substantially as shown.

ALBERT V. OCONE.
